UNITED STATES PATENT OFFICE.

ARTHUR H. ADAMS, OF SPARKILL, NEW YORK, ASSIGNOR TO WESTERN ELECTRIC COMPANY, OF NEW YORK, N. Y., A CORPORATION OF ILLINOIS.

TELEGRAPH-KEY.

1,100,167.

Specification of Letters Patent. Patented June 16, 1914.

Application filed February 16, 1912. Serial No. 678,026.

To all whom it may concern:

Be it known that I, ARTHUR H. ADAMS, citizen of the United States, residing at Sparkill, in the county of Rockland and State of New York, have invented a certain new and useful Improvement in Telegraph-Keys, of which the following is a full, clear, concise, and exact description.

This invention relates to printing telegraphs and devices of like character in which a plurality of lever keys are used for making an electrical contact.

More particularly, its object is to provide a means whereby the contact is made at the end of the downward stroke of the key and is not broken until the key reaches the end of its upward return stroke. In this manner the duration of the contact is controlled by the time required by the key in returning to its normal position, assuming that the key is free to return to its upward position immediately upon its reaching the end of its downward stroke.

Another object of this invention is to combine with the above feature a means to prevent more than one key being depressed at a time, making it necessary for the electrical contact made by one key to be broken before another contact can be made.

In the drawings—Figure 1 is a side elevation of the device; Fig. 2 is a front elevation of the contact mechanism with the key in its normal position, while in Fig. 3 the contact mechanism is shown with the key down; Figs. 4 and 5 show in detail the forward ends of the contact springs in their open and closed circuit positions respectively.

Through a slot in the forward portion of the frame 40 passes the forward extension 13 of the lever 10, carrying the finger key 12. The upper and lower edges 41 and 42 of this slot limit the movement of the keys. On the upper portion of the lever is formed an upwardly and backwardly curved extension 11, while the lower portion extends backward being pivoted at the point 43 to a bar 14 which runs perpendicular to the plane of the lever. Between the extension 11 and the lower portion of the section 37 is an L-shaped frame 15, the horizontal portion of which supports the contact-making device and the vertical portion supports the mechanism for the preventing of more than

one key being depressed at a time. A hook 55 21 is formed on the lever to which is fastened one end of a backwardly extending wire 22. Fastened to the other end of this wire is one end of a retracting spring 23, the other end of said spring being secured 60 to a portion 24 of the frame 40.

The contact mechanism consists of two parallel anvil springs 25 and 26 supported by an insulating block 27 attached to the frame 15. The ends 32 and 36 of these 65 springs are provided with projections 33 and 34. Between these two projections 33 and 34 and through holes in the members 15 and 20 passes a vertical rod 18. A sleeve 19 of insulating material is secured to and 70 covers a portion of the rod 18, and is of such a length and so placed that when the lower end of the sleeve 19, which forms a shoulder, rests upon the member 20 (Fig. 3), the upper end of said sleeve will be 75 slightly below the projections 33 and 34 of the contact springs. In this lower position of the rod 18, as shown in Figs. 3 and 5, the contacts 29 and 30, mounted on said springs, come in contact with the points 35 80 on the post 28, closing the circuit between the two springs. The post 28 is secured to but insulated from the frame 15, and it is so located that its upper portion carrying the contact points 35 is between the two contact 85 blocks 29 and 30 carried by the springs 25 and 26. When the rod 18 moves to its upper position, as shown by Figs. 2 and 4, the sleeve 19 comes between the two projections 33 and 34, forces the two springs 25 and 26 90 apart, and breaks the contacts of the two springs with the post 28, thereby opening the circuit.

The rod 18 is pushed downward by the extension 11 and then it is raised by the upper face of the lever coming in contact with its lower end. It will be noticed that the distance between the lower face of the extension 11 and the upper face of the lever is greater than the length of the rod 18, 100 so that when the key is operated it travels nearly its full downward stroke before the extension 11 comes in contact with the rod 18 with the result that the sleeve 19 does not clear the projections 33 and 34 until the 105 key has reached its lowest position. In other words, the contact of the two springs with the post 28, and consequently the clos-

ing of the circuit, does not occur until the finish of the downward stroke. In like manner the lower end of the rod 18 is not engaged by the portion 37 of the lever 10 until said lever has nearly reached the end of its upward stroke, so that the contact springs 25 and 26 are not spread apart and the circuit opened until the key 12 has reached its normal position; the circuit remaining closed during the return stroke of the key. Hence, the length of time that the circuit is closed is determined by the time taken by the key in its upward movement, which time is dependent upon the tension of the spring 23.

As previously stated, the lower portion of the frame 15 supports the mechanism for preventing more than one key being depressed at a time. This is accomplished in the following manner; the member 20 is bent nearly at a right angle so that its lower edge is parallel to the lower edge of the frame 15. This forms an inverted trough through the slots in the sides of which pass the keys. Between the lower edges of said trough pass a series of parallel rods 16, said rods being spaced below and between the levers so that the lower portion of the lever passes between two of these bars as shown in Fig. 3. Over the upper surface of these parallel bars 16 is placed a ribbon 17, sufficiently loose to permit a key to pass down between two parallel bars. When the key is in its downward position the ribbon is drawn down into the space between two of the parallel bars and around the lower edge of the lever. When in this position (Fig. 3) the entire ribbon 17 is taut so that no other key can be operated until the one now down has been restored to its normal position, since the lower edge of any other key lever will be prevented from passing

between two of the parallel bars 16 by said tautness of the ribbon 17.

What I claim is:

1. In a device of the character described, the combination with a plurality of pivotally mounted key levers, a plurality of contact-making elements arranged in pairs, each pair being individual to a key lever, a plunger element for each pair of contacts operated by the key levers, means carried by said plunger elements for preventing contact of the contact plates except at the end of the stroke of the key levers, in combination with means comprising a plurality of parallel rods, and a flexible member on said rods and in operative relation to said key levers whereby but one key lever can be fully depressed at any one time. 60

2. In a device of the character described, a plate having a plurality of slotted depending members, a bar mounted parallel to the depending members, a plurality of key levers pivotally mounted on said bar and movable in the slotted depending members, an insulated mounting block mounted on said plate and carrying a plurality of contact plates mounted in pairs, one pair for each key lever, a plunger located between 70 each pair of contact plates and normally separating the same, means carried by the key levers for moving said plungers, whereby said contact plates move into engagement with each other in combination with means 75 for preventing the depression of more than one key at a time.

In witness whereof, I hereunto subscribe my name this 13th day of February A. D., 1912.

ARTHUR H. ADAMS.
